MULTIPLYING MACHINE

William Lang, New York, N. Y., and George B. Heddendorf, New Brunswick, N. J., assignors to International Business Machines Corporation, New York, N. Y., a corporation of New York

Application September 24, 1937, Serial No. 165,436

7 Claims. (Cl. 235—61)

This invention relates to improvements in accounting machines and more particularly multiplying accounting machines.

The invention has for its principal object the provision of an improved type of multiplying machine in which data are recorded on a record card in accordance with the binary system of numeration. In accordance with the manner of recording an amount on a record card in the binary system a series of index point positions has assigned thereto values representing the successive powers of two and a number is represented in this series of index point positions by perforating the position which equals or the plurality of positions the sum of whose representations equals the amount to be recorded. Thus a number is represented on a record card by one or more perforations lying in a single line with the relative disposition of the perforations determining the value of the number.

A further object of the invention is to provide a machine in which numbers represented in the binary system of numeration are multiplied by the method of computation technically known as duplication. According to the mathematical principles underlying multiplication by duplication a geometrical progression with a ratio of two is formed in which the multiplicand factor is the first term of the series. Thus with a multiplicand factor of, say, 1580, the series would be 1580, 3160, 6320, 12640, 25280, etc. In accordance with the value of the multiplier factor there is selected from this series the term which equals or the plurality of terms which when added together equal the product of the two factors. The procedure is to repeatedly reduce the value of the multiplier as the multiplicand increases. This reduction is termed "halving" so that, if, with a multiplier of 16, the two series are set down as follows:

Multiplicand .. 1580 3160 6320 12640 25280
Multiplier ----- 16 8 4 2 1

the product 25280 is obtained and is found above the multiplier term whose value is odd. This holds true if all other terms in the multiplier series are even.

Where more than one odd term appears in the multiplier series, the product is the sum of the multiplicand terms above the odd multiplier terms thus:

Multiplicand .. 1580 3160 6320 12640 25280
Multiplier ----- 18 9 4+ 2 1

55 Here the product is 3160+25280=28440. It is to

be noted that the fractions resulting from "halving" the odd numbers are disregarded. Again, for the problem 1580×15 ,

Multiplicand --- 1580 3160 6320 12640 8
Multiplier ----- 15 7+ 3+ 1+ 5
the product is $1580+3160+6320+12640=23700$.

It will be observed that in building the parallel series of numbers that the effect has simply been to restate the problem in terms of different factors, thus:

$1580 \times 16=3160 \times 8=6320 \times 4=12640 \times 2$, etc.

and

$1580 \times 18=3160 \times 9=6320 \times 4\frac{1}{2}=15$
(12640×2) + 3160, etc.

It is to be further observed that where the fraction $\frac{1}{2}$ is involved, such product may again be restated as in the expression:

$6320 \times 4\frac{1}{2}$ to read $(6320 \times 4) + 3160$

It follows then that the problem of 1580×15 may be restated as follows:

$1580 \times 15=(3160 \times 7)+1580=25$
(6320×3) + 3160 + 1580 =
(12640×1) + 6320 + 3160 + 1580 = 23700

From this it is derived that whenever the multiplier term of the series is odd the companion multiplicand term is selected as a term of the product sum.

A machine in which this method of multiplying is applied to numbers expressed in the decimal system is shown and described in the copending application of Lang and Heddendorf, Serial No. 99,370, filed September 4, 1936. In such machine three accumulators are employed, one to receive and build up the progressive series of multiplicand terms, a second to receive and build up the series of multiplier terms, and a third to receive under control of the first two all the terms of the multiplicand series whose multiplier companion terms are odd.

When factors are expressed in the binary system of numeration the multiplying procedure is extremely simplified and the multiplying operation may be effected in a very short space of time.

A further object of the invention is to provide a record card arranged to receive perforations representing numbers expressed in the binary system.

A further object is to provide a machine for sensing a record card for binary numbers representing factors during a cycle of the machine,

compute the product during a further cycle, and punch back the result in the record card in the third cycle.

A further object of the invention is to provide 5 mechanism for selectively reading a binary number from any recording position on the record card and punching back the result of a computation in any recording position of the card.

Further objects of the instant invention reside 10 in any novel feature of construction or operation or novel combination of parts present in the embodiment of the invention described and shown in the accompanying drawings whether within or without the scope of the appended claims and 15 irrespective of other specific statements as to the scope of the invention contained herein.

In the drawings—

Fig. 1 is a central section through the card feeding, sensing, and punching section of the 20 machine.

Fig. 2 is a specimen of a record card perforated in accordance with the binary system of numeration.

Figs. 3 and 4 represent diagrammatically the 25 theory of operation as applied to two different multiplying problems.

Fig. 5 is a wiring diagram of the electric circuits of the machine.

Fig. 6 is a diagrammatic representation of one 30 order of a binary accumulator.

Fig. 7 is a view showing the accumulating devices in another position.

Fig. 8 is a view of a settable switching device.

Fig. 9 is a detail taken on lines 9—9 of 35 Fig. 8.

Fig. 10 is a fragment of a record card showing a modified arrangement of the recording positions for the different values.

Fig. 11 is a portion of the circuit diagram 40 modified for the handling of a record card such as Fig. 10.

Fig. 12 is a timing diagram of the contact devices of the machine.

Figs. 13 and 14 are details of emitters 45 employed for carrying out the multiplying operations.

Record card

Referring now to Fig. 2, the manner in which 50 the numbers are recorded on the record card will first be described. The card is provided with three fields headed MP, MC, and Product, and the columns of the several fields are identified as representing various powers of 2. To record a 55 multiplier of, say, 11, a perforation is made in the three columns representing 1, 2, and 8 whose sum is 11, these three figures being the three powers of 2 whose sum is 11. Similarly, to record a multiplier such as 12, perforations are made 60 in the positions representing 4 and 8, these being the second and third powers of 2. It is to be noted that with a record card as shown having twelve horizontal recording lines, twelve different numbers may be recorded in the MP field. For 65 the purposes of explanation and to avoid a multiplicity of like connections in the circuit diagram, the number of recording positions in the MP and MC fields have been limited to four, but it will be understood that by providing further columns 70 in each of these fields, larger numbers may be recorded. Thus, as in the product field where eight columns are provided, the number 144 is recorded along the fourth horizontal line and is represented by perforations in the columns designated 75 2^4 and 2^7 the sum of which is 144. Like-

wise the number 66 is represented in the product field by a perforation in the column representing 2^1 and 2^6 .

Operating principle

Referring to Fig. 3, there is shown the analogy when multiplying by duplation, between numbers expressed in the decimal system, and numbers expressed in the binary system. The factors 11 and 6 are to be multiplied. Adjacent to these 10 numbers is represented the binary representation of the same and the perforation columns are headed with the actual values of the various powers of 2 so that the number represented may be more readily identified.

First following through the procedure involved in multiplying the decimal values by duplation, the MC 6 is "doubled." At the same time the MP 11 is halved with the fractional remainder disregarded. This doubling and halving is concurrent and is repeated until the MP is reduced to 1 as indicated. Whenever the MP factor is odd, the accompanying MC amount is transferred to a product accumulator, the entry being represented on the column farthest to the right in Fig. 3. Thus for the problem chosen the amounts 6, 12, and 48 are transferred to the product accumulator, the sum of these amounts being 66 which is the answer sought.

Expressed in the binary system, the number 11 30 represents the three perforations in columns headed 1, 2, and 8. Half of this number (disregarding the fractional remainder) is 5 which is represented by a perforation in columns headed 1 and 4. Half of this is represented by a perforation in column 2, and again half the result is represented by a perforation in column 1. Likewise the MC factor 6 is represented by a perforation in columns headed 2 and 4, twice the amount by perforations in columns headed 4 and 8, twice 40. that amount by perforations in columns headed 8 and 16 and so on.

It will be observed in connection with the MC amount that doubling the number is obtained by causing a lateral shift one step toward the right of the coded perforations and for the MP factor the converse is found in that a lateral shift one step toward the left serves to halve the number. It will also be observed that, inasmuch as in the series of powers the only power 50 representing an odd number is the very first power, any odd number represented in the binary system will include the first term of the series which is the zero power of 2. Thus 11, 5 and 1 are odd numbers and in each of these cases the corresponding MC is transferred to the product accumulator. This accumulator is arranged to receive unit entries and to carry from order to order for every second entry.

The various vertical columns in Fig. 3 of the 60 product accumulator represent denominational orders into which units are entered in the positions corresponding to the coding of the numbers entered and carrying operations take place from lower to higher powers. Thus a unit entry into each position headed 2 and 4 indicates an entry of 6. Unit entries in the columns headed 4 and 8 indicate an entry of 12, and a unit entry in each of the columns headed 16 and 32 represents an entry of 48, the result of the successive entries 70 being 66.

In applying the relationships just explained to a mechanical embodiment, the MC factor is represented on a series of contacts, one for each power of 2, by closing contacts relating to the powers 75

whose sum equals the MC factor. A similar set of contacts represents the MP factor in the same manner. The MC contacts are wired to a column shift device so that the contacts are arranged to transmit an impulse to the correspondingly numbered orders of a binary accumulator. A testing device is provided for testing the setting of the MP set of contacts in succession. Testing of the first position will determine that the MP is odd and this will cause the MC set of contacts to transmit an impulse to the corresponding accumulating positions. Following this the column shift changes the position so that the MC positions are connected to the next higher accumulator positions and the testing device tests the next MP contacts, finding a setting here and determining from this fact that half the number is odd, it causes the MC contacts to transmit impulses to the higher orders of the accumulator, thereby, in effect, entering twice the MC therein. Following this, the relationship is again shifted and the testing device now tests the third position of the MP contacts and finds, due to the non-set contacts, that the number is now even and therefore no transfer takes place and the column shift advances a further step. Finally, the last position of the MP set of contacts is tested to find an odd condition causing transfer of the MC setting to the product accumulator in the order representing entry of 48. In this wise, multiplication of two binary numbers is effected by the simple provision of a set of ordered contacts for the MP factor, a set of ordered contacts for the MC factor, and a single binary accumulator.

In Fig. 4 is diagrammatically represented a further problem in which an MP of 12 is multiplied by an MC of 12, resulting in a product of 144. In this case the number itself is even so no transfer takes place of the number. Half the number is also even so again transfer of twice the number does not take place. Further testing shows that 3 is odd and 1 is also odd so transferring takes place in succession of 4 times the number and 8 times the number, the sum of the two powers resulting in 144.

Card handling mechanism

Before describing the circuit connections through which the multiplying is effected, a description will be given of the various mechanical units of the machine. Referring to Fig. 1, the record cards C are placed in the hopper 10 of the machine from which they are fed singly by a picker 11 which is mounted for vertical reciprocation. Motive power is obtained from the main drive shaft 12 which may be driven by any suitable source of power to maintain it in constant rotation. The shaft 12 carries a gear 13 which meshes with and drives a gear 14 freely mounted on the card feed shaft F. Secured to gear 14 is a clutch driving element 15 which is consequently in constant motion. Lying in the plane of clutch element 15 is a spring-pressed dog 16 which is carried by and pivoted to a cam 17. An armature latch 18 normally holds the pawl 16 out of engagement with the driving element 15. Upon energization of magnet 19 latch 18 is rocked counterclockwise to release pawl 16 whereupon its spring will move it into engagement with the driving element 15 to cause rotation of cam 17.

The cam 17 is secured to shaft F so that the shaft will rotate in unison with the driving element 15. The cam 17, as it rotates, will rock a

bell crank follower lever 20 and through a link 21 oscillate arms 22 which have pin and slot connection with the card picker 11. The downward movement of picker 11 will advance a card C from the feed magazine 10 to the uppermost pair of feed rollers 23 which continue the downward movement of the card to further pairs of feed rollers 23. The several pairs of feed rollers are interconnected by gears generally indicated 24 and are driven by a suitable gear secured to the shaft F so that the rollers 23 are in motion during the rotation of shaft F.

The record cards C (Fig. 2) are placed in the magazine 10 so that the "9" index point positions lead and the cards will pass the sensing station 15 comprising individual sensing brushes 25 and common contact roller 26 in the order 9, 8, 7, . . . 0, X, R. For each revolution of shaft F a record card will be advanced from the hopper to a position shown in Fig. 1 in which the card is in position with the brushes 25 about to sense the "9" index point positions. During the second cycle of shaft F the card is advanced to the punching station which comprises a plurality of rows of punches 27 spaced in accordance with the arrangement of the index point positions of the record card. The gate 28 interrupts the leading edge of the card and holds the same in position until punching has been effected. The gate 28 is connected by a link 29 to a bell crank cam follower 30 whose roller cooperates with the cam 31 secured to shaft F. As the cards advance toward the sensing position, they will engage and rock a pivoted card lever 32 which will cause closure of card lever contacts designated CLC.

The punching devices are operated from a shaft designated P upon which is freely mounted a gear 33 to which is secured clutch driving element 34. Cooperating with element 34 is a spring-pressed pawl 35 which is carried by a cam 36. Lying in the plane of clutch element 35 is an armature pawl 37 which normally engages and holds the pawl 35 out of engagement with the driving element 34. Energization of clutch magnet 38 will cause the latch 37 to release pawl 35 for engagement with driving element 34 upon which shaft F, to which cam 36 is secured, will rotate. Cam 36 cooperates with follower lever 40 whose upper extremity is connected through arm and link connection 41 to a shaft 42. Upon the shaft is secured a bail 43 which extends across the upper edges of a plurality of sliders 44. Sliders 44 are suitably mounted for vertical reciprocation and are normally urged upward by their springs 45. The lower extremity of each slider carries a resiliently mounted interposer 46 which will pass the punches 27 in the related column in order. As the slider 44 moves upwardly, notches 47 will pass the nose of a pawl 48 in succession. During the upward movement of the slider, energization of punch selecting magnet 49 will attract its armature 50 and release pawl 48 for engagement in one of the notches 47. The notch engaged will depend upon the time of operation of the magnet 49.

After the sliders 44 have been positioned, punch plate 51, which is mounted for horizontal reciprocation, will be moved toward the left to force the interposers 46 against the selected punches 27 and force the same through the record card. The plate 51 has connected to it a link 52 whose other end is connected to a bell crank follower 53 which is operated by the cam 54 secured on shaft P.

A further shaft, designated M, is provided on 75

which is freely mounted a gear 55 which, through an idler 56, is driven from the main drive shaft 12. Secured to gear 55 is a clutch driving element 57 which cooperates with a dog 58 carried by and pivoted to a disk 59. Cooperating with the dog is an armature latch 60 and a controlling magnet 61. Energization of magnet 61 will release dog 58 for engagement with element 57 and shaft M will make a complete rotation during which multiplying operations take place.

Testing and column shift commutators

Referring to Fig. 13, the shaft M carries a pair of electrically connected commutator brushes 62 which, as the shaft rotates, successively connects each of a ring of contact segments M2 with a common conducting ring 64. A similar pair of brushes 65 (Fig. 14) is carried by shaft M and these brushes successively connect each of the ring of common segments M3 with a common conducting ring 66. There is a single ring of segments M2 provided and a number of rings of segments M3 as will be explained in connection with the circuit diagram. Also carried on shaft M are a pair of cams controlling contacts M1, M4 represented on Fig. 5 and timed as indicated in Fig. 12.

Sensing and punching line selectors

Referring to Figs. 8 and 9, the shaft F carries a commutator 67 which has an outer conducting ring 68 against which a wiper 69 rubs. Embedded in the commutator is a series of contact segments F1 which, as the commutator rotates, contact a wiper 70 in succession. On the face of the commutator and in line with each of the segments F1 is a slide 71 which carries a metallic conductor 72. When the slide is in the dotted line position shown in Fig. 9 the corresponding segment F1 is electrically connected to the common ring 68 and when the slide is moved to its full line position, this connection is broken. In sensing the record card, if the factors to be sensed are perforated in, say, the fourth horizontal line, the 4 slide 71 is moved outwardly from the shaft F to connect its segment F1 with the common ring and all of the other slides are in their inner position as shown in Fig. 8. The circuits controlled through the commutator device will be more fully explained in connection with the circuit diagram.

Accumulator

Referring now to Fig. 6, a form of binary accumulator is diagrammatically disclosed and represents in effect, a form of stepping relay provided with denominational order carry mechanism. Each order comprises a ratchet wheel 80 which is integral with the cam 81 and a carry ratchet 82. An adding magnet 83, upon energization, will rock its armature 84 and through pawl 85 will advance the ratchet 80 one tooth. In so moving, the cam 81 will cause closure of a pair of contacts 86. Upon the next energization of magnet 83, ratchet 80 will advance the second step and contacts 86 will again open. The relative positions of the parts after the first impulse to the adding magnet 83 are shown in Fig. 7 with the contacts 86 closed.

For every second increment of advance of the ratchet 82, one of its camming projections will cause momentary closure of a pair of contacts 87 which will energize a carry magnet 88 in the next higher denominational order. This magnet will attract its armature 89 and through an arm 90 will cause its spring-pressed pawl 91 to ad-

vance ratchet 80 in the next higher order one step. The parts are so proportioned that if the next higher order is receiving an entry through its adding magnet, it will have advanced its ratchet 80 a sufficient distance before its carry magnet is energized so that the carry pawl will engage the proper tooth to enter the carried unit.

Means for resetting the accumulator orders is provided in the form of a reset magnet 92 which, through its armature 93, rocks a cross shaft 94. From this shaft depend arms 95, one for each order of the accumulator. Each arm carries a spring-pressed pawl 96 which is moved from the full line position of Fig. 6 to its dotted line position and in those orders in which the ratchets are displaced one step, the pawl 96 will engage one of the projections of ratchet 82 and advance the same one step. In those positions in which the ratchet is in its home position, no movement will be had.

Circuit diagram

The operation of the machine in which a pair of factors is sensed on the record card, their product computed, and punched back in the record, will now be explained with particular reference to the circuit diagram, Fig. 5. In Fig. 2 the record card C contains the MP factor 11 and the MC factor 6 in the eighth horizontal row. These two factors are to be multiplied together and the product punched back in the same row in the product field. Referring to Fig. 5, the sensing brushes 25 which traverse the MP field are wired to plug sockets 100 from which plug connections 101 are made to plug sockets 102. The brushes 25 which traverse the MC field are similarly connected to another set of plug sockets 102. The punch selecting magnets 49 are wired to sockets 103 from which plug connections 104 are made to plug sockets 105. These plug connections are made from the orders of the accumulator to the punch magnets 49 related to the field in which the product is to be punched. Since the factors are to be sensed from the eighth horizontal line, the 8 slide 71 of the line selecting commutator on the F shaft is moved to its outer position and since the product is to be punched back in the 8 line, the 8 slide 71 of a similar commutator on the P shaft is also moved to its outer position. With the plug connections made as indicated and with cards placed in the supply magazine 10, the machine is ready to commence operation.

Depression of the start key will close contacts 106 to complete a circuit from negative side of line 107, through the start key contacts 106 and card feed clutch magnet 19 to the left or positive side of line 108. It is assumed that the main drive shaft 12 is in constant operation with a suitable source of power so that energization of magnet 19 will couple the card feed shaft F for rotation and this shaft will now turn to cause advance of the first card from the supply magazine. During this cycle the F cams operate and toward the end of the cycle contacts F3 close to energize the multiplying clutch magnet 61 which releases shaft M for a cycle of operations which is an idle cycle at this time since no effective card reading has yet been entered. The first card at this time is in the position indicated in Fig. 1 with the "9" index point positions ready to pass the sensing brushes. Near the end of the revolution of the shaft M contacts M4 close, energizing the punch clutch magnet 38 to initiate a cycle of operations of shaft P. During this cycle, which is also an idle one at this time, the punch

mechanism operates, but since no card is in position to be punched, the operation is of no effect.

Near the end of the punching cycle, cam contacts P3 close again energizing the feed clutch magnet 19 provided card lever contacts CLC are closed denoting that the first card has been advanced to the brushes and shaft F enters upon another cycle of operations to advance the card past the sensing brushes 25.

- 10 During this passage of the cards by the brushes 25 the commutator segments F1 pass the wiping contact 70 in succession as the correspondingly numbered lines of the record card pass the brushes. Thus, since only the 8 segment F1 is active, when the 8 line of the card is at the brushes, parallel circuits will be traced through each of the perforated positions which circuits are traceable from left side of line 108 to wiper 69, conducting ring 68, slide 71, the "8" segment F1, wiper 70, common contact roll 26, thence through each of the perforated positions to plug sockets 100, connections 101, plug sockets 102, thence through relay magnets 109 and 110, wire 111, to right side of line 107. Thus, for the example chosen, the first, second and fourth magnets 109 and second and third magnets 110 are energized in response to the sensing of the two factors 11 and 6 on the eighth line of the card. Relays 109 close contacts 109a and relays 110 close contacts 110a, completing circuits from line 107, wire 111, relay magnets 112 and 113, respectively, through contacts 109a and 110a, wire 114, contacts M1, to line 108. Relays 109 and 110 also close additional contacts 109b and 110b which accordingly take a setting corresponding to the arrangement of perforations representing the two factors.

Specifically, the first, second, and fourth contacts 109b are closed and the second and third contacts 110b are also closed and will remain in this condition until near the end of the next or multiplying cycle when contacts M1 open momentarily to drop the holding circuits. Near the end of the card feed cycle, as explained, closure of contacts F3 energize the multiplying clutch magnet 61 and the shaft M now makes a cycle of operation. During this cycle the brush 62 successively traverses the segments M2 and the brushes 65 successively traverse the segments M3, the timing being such that brush 62 engages the segment M2 before brush 65 engages the corresponding segment M3. Since for the example chosen the first contact 109b is closed a circuit is traceable when brush 62 engages the first segment M2 from line 108 through transfer magnet 115, common conductor 64, brush 62, segment M2, contacts 109b, wire 111 to line 107. Magnet 115 will thereupon close its contacts 115a connecting the contacts 110b to line 107. As the brushes 65 contact the first of the segments M3 in each of the four positions, the four contacts 110b will be electrically connected to the first four adding magnets 83, counting from the left, and circuits will be completed through these magnets in accordance with the condition of the contacts 110b. Since, for the example chosen, the two central contacts are closed, these circuits will cause closure of the second and third magnets 83, the circuits being traceable from line 107, contacts 115a, the second and third contacts 110b, the second and third conductors 66, the second and third brushes 65, the first segments M3 of the second and third group, and the appropriate wires 116 leading to the second and third adding magnets 83, thence through wires 117, to line 108. In this manner the value 6 is entered into the binary ac-

cumulator. As brush 62 continues, it will next test the setting of the second pair of contacts 109b. Finding these closed, it will again cause energization of the transfer magnet 115, causing closure of contacts 115a and now the transfer circuits will pass through the second segments M3 in the two groups related to the two central contacts. The wires 116 from these segments, however, run to the third and fourth magnets 83 so that, in effect, the value 12 is entered into the 10 binary accumulator (see Fig. 3).

During the interval between the sensing of the segments M2, carry operations take place whenever more than one unit is entered into any order which causes closure of related contacts 87 and 15 energization of the carry magnet 88 of the next higher order. Sufficient time is provided between segments M2 for multiple carry operations to take place in succession and since carry operations involve only a momentary energization of a 20 magnet, this operation is very rapid. When brush 62 encounters the third segment M2, no circuit is completed since contacts 109b in this position are open and consequently there is no transfer circuit completed during this interval. Finally, 25 the fourth segment M2 is engaged by the brush 62 and again magnet 115 is energized and transfer circuits are completed, this time in orders of the accumulator representing an entry of 48.

On the circuit diagram seven of the seventeen 30 testing positions indicated on the timing chart are shown for the brushes 62 and 65 with the circuit connections for only four of the multiplier positions shown. With the complete seventeen positions wired, numbers up to 41,536 may be handled by the machine. Near the end of the multiplying cycle, cam magnets M1 open and drop the holding circuit for the relays and cam contacts M4 close to energize the punch shaft magnet 38. At this time the readout contacts 86 of 40 the binary accumulator are set to represent the product which in the present case is 66 so that the second and seventh contacts 86 are in closed position and the others are open. During the rotation of shaft P the segments P1 traverse the brush 72 and when the "8" segment 70 is at the wiper, a series of parallel circuits are completed which are traceable from line 108, wiper 69, conducting ring 68, slider 71 in the "8" position, "8" segment P1, wiper 70, wire 118, the second and 50 seventh contacts 86, thence through the second and seventh punch selecting magnets 49 to line 107. Energization of the magnets at this time will stop their related punch slides with their interposers 46 (see Fig. 1) opposite the related 55 punches in the eighth horizontal line of the card which is now in punching position and punching will be effected to perforate the card as shown in Fig. 2, the location of the holes representing the first and sixth powers of 2.

Near the end of the punching operation, contacts P2 close to energize the reset magnet 92 which causes restoration of the readout contacts and at the same time contacts P2a open to prevent the completion of carry circuits during re-setting operations. As explained, when the punching cycle is completed, cam contacts P3 close to initiate a new series of operations during which the next card is analyzed, its factors multiplied, and the product punched back on the 70 card. These operations take place in three successive cycles.

In Figs. 10 and 11 is shown a modified form of the invention in which the record card C has the factors disposed one above the other and the 75

product is punched in columnar alignment therein. For this arrangement, a group of contacts 200, 201 are provided which are plug connected between the sensing brushes 25 and the entry 5 sockets 102 of the magnets 109 and 110 as shown. Inasmuch as the MC factor is on the sixth line, the sixth slide 71 is moved outwardly and since the MP factor is on the third line, the third slide is also moved outwardly. A cam 202, adjustably 10 mounted on a shaft F, is adjusted to shift the contacts 200, 201 to their reverse position between the sensing of the sixth line and the third line so that when the sixth line is sensed, the circuits extend from the brushes 25, contacts 15 201, to the MC magnets 110 and when the third line is sensed, contacts 201 will be opened and contacts 200 will be closed during the entry of the MP from sensing brushes 25, through contacts 200 and the MP magnets 109. The read- 20 out contacts 86 of the accumulator are plug connected to the punch selecting magnets in the positions indicated so that during the punching operation, punching will take place as shown.

While there has been shown and described and 25 pointed out the fundamental novel features of the invention as applied to a single modification, it will be understood that various omissions and substitutions and changes in the form and details of the device illustrated and in its operation 30 may be made by those skilled in the art without departing from the spirit of the invention. It is the intention therefore to be limited only as indicated by the scope of the following claims.

What is claimed is as follows:

- 35 1. In a machine of the class described, a binary accumulator having ordered sections, a settable device having similarly ordered elements settable to represent a number expressed in the binary system of numeration, means for connecting said 40 settable elements to the corresponding accumulator sections and to successively higher ordered sections, entering means for said accumulator actuated through said connections for repeatedly entering the binary number in progressively higher 45 orders, a second settable device having ordered elements settable to represent another number expressed in the binary system of numeration, and means including said second settable device for selecting the section of the accumulator for receiving entries and for rendering said connections 50 effective for causing entering in only the selected sections of the accumulator.
2. In a multiplying machine, a series of contacts ordered to represent the successive powers 55 of two, a second series of like ordered contacts, means for adjusting each set of contacts to represent a number in the binary system of numeration, a binary accumulator ordered to represent the successive powers of two, connections between said accumulator and one of said series of contacts, column shift devices for shifting said connections so that said series will be connected in turn to orders of the accumulator representing the number represented on said set of contacts and multiples of said number, entering means controlled by said connections and means controlled by said other series of contacts for completing said connections for control of said entering means.
- 70 3. In a multiplying machine, a series of pairs of contacts ordered to represent the successive powers of two, means for entering a number of said pairs of contacts by causing closure of the pair of contacts of the series the sum of whose 75 represented powers equals the number, means for

testing each pair of contacts in order to determine which pairs have been closed, a second series of pairs of contacts similarly ordered and similarly closed to represent another number, a binary accumulator, entering means therefor, means for 5 partially establishing circuit connections from said second series of contacts to the entering means of said accumulator for each operation of said testing means and means controlled by said testing means for causing completion of said 10 connections for each order of said first series of contacts in which a pair of contacts is closed.

4. In a multiplying machine, a series of like adjustable elements ordered to represent the successive powers of two, a second series of like ordered elements, means for adjusting each set of elements to represent a number in the binary system of numeration, a binary accumulator ordered to represent the successive powers of two, 15 connections between said accumulator and one of 20 said series of elements, column shift devices for shifting said connections so that said series will be connected in turn to orders of the accumulator representing the number represented on said set of elements and multiples of said number, 25 entering means controlled by said connections and means controlled by said other series of elements for completing said connections for control of said entering means.

5. In a multiplying machine, a series of set- 30 table elements ordered to represent the successive powers of two, means for entering a number on said series of elements by effecting a setting of the elements of the series the sum of whose represented powers equals the number, means for 35 testing each element of the series in turn to determine which elements have been set, a second series of settable elements, similarly ordered and similarly set to represent another number, a binary accumulator, entering means therefor, 40 means for partially establishing connections from said second series of elements to the entering means of said accumulator for each operation of said testing means and means controlled by said testing means for causing completion of said 45 connections for each order of said first series of elements in which an element is set.

6. In a multiplying machine, a series of like adjustable elements ordered to represent the successive powers of two, a second series of like ordered elements, means for adjusting each set of elements to represent a number in the binary system of numeration, a binary accumulator having 50 ordered sections to represent the successive powers of two, column shift devices intermediate 55 one of said series of elements and said accumulator for associating the elements of the series with the accumulator sections, transferring means for repeatedly transferring the number represented on said series of elements to said accumulator, 60 each transfer being routed by said column shift devices to a different set of accumulator sections, means for testing the setting of the elements of the other series of elements, in succession, and means controlled by said testing means for rendering said transferring means effective in accordance with the setting of the elements tested.

7. In a multiplying machine, a pair of contacts representing a predetermined power of two, means for adjusting said contacts to indicate the 70 entry therein of said power of two, a series of contacts ordered to represent the successive powers of two, means for adjusting said series of contacts to represent a number in the binary system of notation, a binary accumulator having 75

ordered sections, each for representing a different power of two, entering means for each section, means for connecting said pair of contacts to the entering means of each accumulator section in turn, means for testing the setting of the contacts of said series in turn, said pair of contacts being connected to a different accumulator section for each of the contacts in the series

tested, and means controlled by said testing means when the contacts tested are adjusted to represent an entry therein of a power of two for rendering said pair of contacts effective to complete a circuit to the entering means of the accumulator through said connecting means. 5

WILLIAM LANG.
GEORGE B. HEDDENDORF.

CERTIFICATE OF CORRECTION.

Patent No. 2,192,612.

March 5, 1940.

WILLIAM LANG, ET AL.

It is hereby certified that error appears in the printed specification of the above numbered patent requiring correction as follows: Page 6, first column, line 72, claim 3, for the word "of" second occurrence, read on; and that the said Letters Patent should be read with this correction therein that the same may conform to the record of the case in the Patent Office.

Signed and sealed this 30th day of April, A. D. 1940.

(Seal)

Henry Van Arsdale,
Acting Commissioner of Patents.
